US00D973074S

(12) **United States Design Patent** (10) Patent No.: **US D973,074 S**
Morrison (45) Date of Patent: **** Dec. 20, 2022**

(54) **PORTION OF A DISPLAY SCREEN WITH A GRAPHICAL USER INTERFACE**

(71) Applicant: **Hoffmann-La Roche Inc.**, Little Falls, NJ (US)

(72) Inventor: **Cassie Catherine Morrison**, Dundee (GB)

(73) Assignee: **Hoffmann-La Roche Inc.**, Little Falls, NJ (US)

(**) Term: **15 Years**

(21) Appl. No.: **29/822,535**

(22) Filed: **Jan. 10, 2022**

(57) **CLAIM**

The ornamental design for a portion of a display screen with a graphical user interface, as shown and described.

DESCRIPTION

FIG. 1 is a front view of a portion of a display screen with a graphical user interface.

FIG. 2 is a second embodiment thereof; and,
FIG. 3 is a third embodiment thereof.

The broken lines illustrating a portion of a display screen form no part of the claimed design.

1 Claim, 3 Drawing Sheets
